(57) **CLAIM**

The ornamental design for a solar charging pile, as shown and described.

DESCRIPTION

FIG. 1 is a perspective view of a solar charging pile showing our new design;

FIG. 2 is a perspective view of the charging pile of FIG. 1 shown in an environment of use;

FIG. 3 is a front view of the solar charging pile of FIG. 1;

FIG. 4 is a back view thereof;

FIG. 5 is a back left view thereof;

FIG. 6 is a front right view thereof;

FIG. 7 is a top view thereof;

FIG. 8 is a bottom view thereof;

FIG. 9 is an enlarged view of the encircled area 9 of FIG. 2; and,

FIG. 10 is an enlarged view of the encircled area 10 of FIG. 4.

The broken lines shown in the figures depict portions of the solar charging pile that do not form part of the claimed design. In FIG. 2, the broken lines depict the use environment of the solar charging pile. This environment forms no part of the claimed design. The dot-dash lines depict the enlarged view boundaries and form no part of the claimed design.
